RAZOR BLADE SHARPENER

Frank R. Chester, Manhattan Beach, Calif.

Application September 6, 1944, Serial No. 552,875

15 Claims. (Cl. 51—161)

1 My present invention relates to a razor blade sharpener.

One of the principal objects of this invention is to provide a razor blade sharpener which is particularly simple and economical of construction, one which is particularly simple to operate, and one which will not readily deteriorate or get out of order.

Another important object of this invention is to provide a razor blade sharpener in which the razor blades of substantially all ordinary makes of safety razors may be sharpened, and in which such blades may be easily and quickly secured in place, and also easily and quickly removed therefrom.

An important object also of this invention is to provide a razor blade sharpener in which a unitary mechanism is provided for moving the blade to be sharpened over an abrasive sharpening means, and also shifting or oscillating the blade for alternately sharpening both sides of one edge, such movements being produced by a circular motion imparted to the blade carrier.

A further important object of this invention is to provide novel means for causing shifting movement of the blade carrier or holder so as to cause ready engagement of both sides of an edge of the blade on the carrier or holder alternately with two spaced apart abrasive sharpening members.

A still further important object of this invention is the provision of a cord for operating the sharpener, and means in association therewith to facilitate endwise movement of a blade carrier operating spool or sheave, and the consequent shifting of the edge of the blade on the carrier or holder, operated by the spool or sheave, against the abrasive members.

With these and other objects in view, as will appear hereinafter, I have devised a razor blade sharpener having certain novel features of construction, combination, and arrangement of parts and portions, as will be hereinafter described in detail and particularly set forth in the appended claims, reference being had to the accompanying drawings, and to the characters of reference thereon which form a part of this application, in which:

Fig. 1 is a perspective view of my sharpener in a preferred form, and its position on a flexible cord, over and by which it is to be operated;

Fig. 2 is a plan view, on an enlarged scale, of the lower portion of the sharpener, with the section taken substantially through 2—2 of Fig. 3;

Fig. 3 is a transverse sectional view thereof, taken through 3—3 of Fig. 2;

2

Fig. 4 is a perspective view of the razor blade carrier, or holder;

Fig. 5 is a fragmentary sectional view thereof, taken through 5—5 of Fig. 2, showing particularly the spool or sheave mounting for operating the blade carrier or holder;

Fig. 6 is a fragmentary view of another type of razor blade which may be sharpened in my sharpener, and showing the approximate relation of the blade fastening means thereto, for fastening the blade to the carrier or holder;

Fig. 7 is a plan view of a slightly modified form of construction of the means of my sharpener for moving the blade holder;

Fig. 8 is a fragmentary elevational view thereof; and,

Fig. 9 is a transverse sectional view thereof, taken through 9—9 of Fig. 7.

My razor blade sharpener, as shown in Figs.

20 1 to 5 of the drawings, is enclosed in a case consisting of bottom and cover case members. The bottom case has a sheet metal member 1 which is hinged at one side to the side 2^a of a sheet metal cover member 2. The bottom case member 25 consists of the member 1 and a body member 3, which may be made of plastic. The member 3 is of U-shape, as shown in Fig. 2, and forms the front and end portions of the lower case member. The member 1 extends over the rear portion of the bottom of the member 3, as shown best in Fig. 3 and by dotted lines in Fig. 2. The casing members are held in closed positions by a resilient latch 2^b at the side opposite the hinge.

The razor blade carrier or holder, shown best in Fig. 4, is formed of sheet metal and is provided with tubular hinge portions, or eyes 4^a into the outer ends of which extend pins 5^a of a rocker 5. This rocker 5 is a flat member having trunnions 5^b extending outwardly beyond its ends from its lower portion. These trunnions are rotatably mounted in ears 1^a struck upwardly from the bottom of the casing member 1.

In the opening between the connecting portion 3^a and the legs 3^b of the U-shaped casing member 3 is positioned a spool or sheave 6 which is rotatably mounted on a spindle or pin 7 secured to and extending upwardly from the bottom wall of the casing member 1. This sheave is adapted to be rotated about the pin by a cord 8 extending from the ends of the case through the leg portions 3^b of the member 3. The intermediate portion of the cord is wrapped with one convolution around the sheave 6, as shown in Figs. 2, 3, and 55 4. While the cord 8 is held taut, the movement

of the case along the cord causes the sheave to be rotated.

The blade carrier or holder 4 is positioned directly over the sheave and is pivotally connected at its median portion between its ends to the pin 6^a carried by the upper face of the sheave eccentrically with respect to the axis of its bore, thus forming a crank portion at the upper end of the sheave. The underside of the head of the pin 6^a is semi-ball shaped and it fits into a semi-spherical recess 4^f near the free edge of the blade carrier or holder.

Rotation of the sheave 6 causes rotary movement of the holder, and results substantially in lengthwise reciprocation of the holder 4 on or with respect to the rocker 5. Rotation of the sheave 6 in the manner stated also causes axial movement of the sheave on the pin 7, by reason of the spiral frictional winding of the cord on the sheave. This causes the holder 4 to be oscillated about the pins 5^a of the rocker 5. The movement of the holder thus requires a ball point between the rotating sheave 6 and the holder 4, as described above.

To facilitate endwise or axial movement of the sheave 6 on the pin 7, in order to increase the engaging force of the blade A upon the abrasive members 9 and 10, the pin 7 may be secured to the case member 1 at a slight angle, the inclination being toward one end of the case, as shown in exaggerated form in Fig. 5.

The blade A which is to be sharpened is removably positioned on or against the upper face of the carrier or holder 4, the blade shown in Figs. 2 and 3 being a conventional two-edged blade. It is held in position by cylindrically shaped portions 4^b at the ends of spring-like members 4^c provided at the opposite ends of the free portion of the holder 4. One edge of the blade is located by an upwardly turned flange 4^d near the pivoted edge of the holder, and the enlarged portions 4^b extend through the central slot A¹ of the blade A, and at the ends of said slot, and resiliently force the blades against the flange 4^d. The cylindrical portion 4^b urges the blade against the flange 4^d. The other or free edge of the blade extends beyond the carrier or holder and this free edge is adapted to engage the adjacent sides of said abrasive members or hones 9 and 10, the former being secured within and at the free portion of the cover 2, while the latter is secured to the member 3 of the lower case member. The adjacent sides of the abrasive or hone members 9 and 10 may be provided with serrations 9^a and 10^a, respectively. As the blade A is drawn across both abrasive or hone members, at the angle shown in Fig. 3, by reason of the circular movement of the holder 4, as described above, both sides of one edge of the razor blade are sharpened.

As the case is moved in the direction of the arrow, shown in Fig. 5, the nature of the winding on the sheave 6 will cause the sheave to be moved upwardly. This will cause the blade A to be shifted against the abrasive member 9. Movement of the case on the cord in the direction opposite to that of the arrow will have the opposite effect upon the sheave in axially shifting the same downwardly on the pin.

The razor blade B, shown in Fig. 6 has a reinforced portion B¹ at one edge. The holder 4 has an elongated recess 4^e for receiving this enlarged reinforcing portion B¹. The same portions 4^b of the springs 4^c enter notches B² at the ends

of the blade B for securing the latter in position on the blade holder.

It is obvious from the above description that the cord 8 over which the sharpener case is drawn in opposite directions may be held taut by securing one end of the cord on a fixed object and holding the other end in one hand, while holding the case in the other hand and drawing such case over the cord.

In the modification shown in Figs. 7, 8, and 9, there is provided a central sheave or spool 15 and sheaves or spools 16 at either side thereof. The axes of these spools are positioned parallel and are located in the same plane extending vertically through the longitudinal portion of the case. They are so positioned that the cord 8 extends consecutively around one side of one end sheave 16 around the opposite side of the center sheave 15, and around the opposite side of the sheave 16. Thus, the cord 8 extends outwardly from the sheaves 16 in substantially the same straight line.

The sheaves are all mounted on pins 17 which extend upwardly from an inverted channel shaped slide 18, the sheaves or spools being rotatably secured thereto by riveting over the outer ends of the pins. At the upper end of the central sheave 15, and on its supporting pin, is mounted a disc 19, and the upper face of the disc lies in the same plane as the upper faces of the sheaves 16. Each of the sheaves 16 and the disc 19 have eccentric pins 20, all of which extend through the carrier or holder 21 for rotating the same, resulting in reciprocating the same with respect to the abrasive members as the sheaves 16 are rotated. The carrier is preferably secured to the pins 20 by riveting the ends of the latter.

It will be here noted that the sheaves 16 rotate in the opposite direction from the sheaves 15, but the disc 19, which is loosely mounted over the upper sheave 15, permits the carrier to be moved without interference with the opposite rotation of the sheave 15.

The legs or flanges of the slide 18 are provided with angular slots 18^a through which extend pins 22, which are secured transversely through the portion 23 of the base or lower case member. The slide 18 is also reciprocally mounted on this portion of the base.

As the case is moved in opposite directions, the sheaves 15 and 16 are rotated in the opposite directions, but the moving force, causing such rotation, will also cause the support 18 to be moved with respect to the supporting base 23 and on the pins 22 thereon, causing the support 18 to be raised and lowered and therefore causing the blade carrier, mounted thereon to be raised and lowered, and the blade A thereon to be alternately forced against the adjacent inclined faces 24 and 25.

Though I have shown and described a particular construction, combination, and arrangement of parts and portions, and a certain modification thereof, I do not wish to be limited to the same, but desire to include in the scope of my invention the construction, combination, and arrangement, substantially as set forth in the appended claims.

I claim:

1. In a razor blade sharpener, a supporting means, spaced abrasive surface means thereon, a sheave means carried by the supporting means, means for rotating and axially reciprocating said sheave means, a razor blade carrier, crank means on the sheave means connected to the carrier for

rotating the same, said carrier being capable of holding a razor blade and moving an edge thereof alternately over said abrasive surface means.

2. In a razor blade sharpener, a supporting means, spaced abrasive surface means thereon, a sheave means carried by the supporting means, a cord extending through said supporting means for rotating and axially reciprocating the sheave means, a razor blade carrier, crank means on the sheave means connected to the carrier for rotating the same, said carrier being capable of holding a razor blade and moving an edge thereof alternately over said abrasive surface means.

3. In a razor blade sharpener, a supporting means, spaced abrasive surface means thereon, a sheave means carried by the supporting means, a razor blade carrier, crank means connecting the sheave means to the carrier, said carrier being capable of holding a razor blade, and means for rotating said sheave means alternately in opposite directions and for shifting said carrier and sheave means alternately in opposite direction axially with respect to the sheave means, an edge of said blade being capable of being moved alternately over said abrasive members.

4. In a razor blade sharpener, a supporting means, spaced abrasive surface means thereon, a sheave means carried by the supporting means, a razor blade carrier, crank means connecting the sheave means to the carrier, said carrier being capable of holding a razor blade, a cord extending through the supporting means for rotating said sheave means alternately in opposite directions and for shifting said carrier and sheave means alternately in opposite directions axially with respect to the sheave means, an edge of said blade being capable of being moved alternately over said abrasive surface means.

5. In a razor blade sharpener, a supporting means, spaced abrasive members thereon, a sheave, means for rotating and axially reciprocating the sheave, a rocker pivotally mounted on the supporting means on an axis at substantially a right angle to the axis of the sheave, and a razor blade carrier probably mounted at one edge on the free portion of the rocker, said sheave having a crank connected to the carrier for reciprocating the same with respect to and rocking the same about the rocker, said carrier being capable of holding a razor blade and moving an edge thereof alternately over said abrasive members.

6. In a razor blade sharpener, a supporting means, spaced abrasive members thereon, a sheave, a cord extending through said supporting means for rotating and axially reciprocating the sheave means, a rocker pivotally mounted on the supporting means on an axis at substantially a right angle to the axis of the sheave, and a razor blade carrier pivotally mounted at one edge on the free portion of the rocker, said sheave having a crank connected to the carrier for reciprocating the same with respect to and rocking the same about the rocker, said carrier being capable of holding a razor blade and moving an edge thereof alternately over said abrasive members.

7. In a razor blade sharpener, a supporting means, spaced abrasive members thereon, a sheave rotatably and axially reciprocally mounted thereon on an axis inclined at a slight angle to the perpendicular to the plane between the abrasive members, said inclination being in the direction of the longitudinal extent of the abrasive members, means for rotating and axially reciprocating the sheave, a rocker pivotally mounted on the supporting means on an axis at substantially

a right angle to the axis of the sheave, and a razor blade carrier pivotally mounted at one edge on the free portion of the rocker, said sheave having a crank connected to the carrier for reciprocating the same with respect to and rocking the same about the rocker, said carrier being capable of holding a razor blade and moving an edge thereof alternately over said abrasive members.

10. 8. In a razor blade sharpener, a supporting means, spaced abrasive members thereon, a sheave rotatably and axially reciprocally mounted thereon on an axis inclined at a slight angle to the perpendicular to the plane between the abrasive members, said inclination being in the direction of the longitudinal extent of the abrasive members, a cord extending through said supporting means for rotating and axially reciprocating the sheave, a rocker pivotally mounted on the base on an axis at substantially a right angle to the axis of the sheave, and a razor blade carrier pivotally mounted at one edge on the free portion of the rocker, said sheave having a crank connected to the carrier for reciprocating the same with respect to and rocking the same about the rocker, said carrier being capable of holding a razor blade and moving an edge thereof alternately over said abrasive members.

9. In a razor blade sharpener, a supporting means, a slide reciprocally mounted on the supporting means in such a manner as to be alternately raised and lowered as the slide is reciprocated, a plurality of sheaves rotatably mounted on the slide on axes perpendicular to the plane of reciprocation thereof, a cord laced around each of said sheaves, a disc mounted at the upper end of an intermediate sheave, a razor blade carrier mounted on the upper ends of two of the sheaves and the disc, crank means connecting the latter sheaves and disc to said carrier, and spaced apart abrasive members on the supporting means, said carrier being capable of holding a razor blade and moving an edge thereof alternately over said abrasive members.

45. 10. In a razor blade sharpener, a supporting means, a slide reciprocally mounted on the supporting means in such a manner as to be alternately raised and lowered as the slide is reciprocated, two end sheaves and an intermediate sheave rotatably mounted on the slide on axes perpendicular to the plane of reciprocation thereof, the axes lying substantially in the same plane, a cord laced around each of said sheaves, causing the end sheaves to be rotated in the same direction, a disc mounted at the upper end of the intermediate sheave, a razor blade carrier mounted on the upper ends of the end sheaves and the disc, crank means connecting said end sheaves and disc to said carrier, and spaced apart abrasive members on the supporting means, said carrier being capable of holding a razor blade and moving an edge thereof alternately over said abrasive members.

11. In a razor blade sharpener of the class described, a supporting means, abrasive surface means thereon, a blade carrier, crank means carried by the supporting means and connected to the carrier for moving the latter in a circular path in substantially the plane of the blade, and means for arcuately moving and axially reciprocating the crank, said carrier being capable of holding a blade and moving the same in said arcuate path over the abrasive surface means.

12. In a razor blade sharpener, a supporting means, spaced abrasive surface means thereon, a

razor blade carrier, crank means carried by the supporting means and connected to the carrier for moving the latter in a circular path in substantially the plane of the blade, and means for arcuately moving and axially reciprocating the crank, said carrier being capable of holding a razor blade and moving an edge thereof alternately over the spaced apart abrasive surface means.

13. In a razor blade sharpener, a supporting means, a spaced abrasive surface means thereon, a razor blade carrier, crank means carried by the supporting means and connected to the carrier for moving the latter in a circular path in substantially the plane of the blade, and means for rotating and axially reciprocating the crank, said carrier being capable of holding a razor blade and moving an edge thereof alternately over the spaced apart abrasive surface means.

14. In a razor blade sharpener of the class described, a supporting means, abrasive surface means thereon, a blade carrier, crank means carried by the supporting means and connected to the carrier for moving the latter in a circular path in substantially the plane of the blade, means for arcuately moving and axially reciprocating the crank, and means in connection with the carrier for moving the same with respect to the support against and from the abrasive surface means, said carrier being capable of holding a blade and

10 15

moving the same in said arcuate path over the abrasive surface means when moved thereagainst by said moving means.

15. In a razor blade sharpener, a supporting means, spaced abrasive surface means thereon, a razor blade carrier crank means carried by the supporting means and connected to the carrier for moving the latter in a circular path in substantially the plane of the blade, means for arcuately moving and axially reciprocating the crank, and means in connection with the carrier for rocking the same alternately toward the two abrasive surface means, said carrier being capable of holding a razor blade and moving an edge thereof alternately over the spaced apart abrasive surface means as the edge is rocked toward the latter by the rocking means.
